United States Patent Office

Des. 182,305
Patented Mar. 11, 1958

182,305

ESCUTCHEON OR SIMILAR ARTICLE

Fred J. Russell, Los Angeles, Calif.

Application January 3, 1956, Serial No. 39,546

Term of patent 14 years

(Cl. D50—6)

Fig. 1.

Fig. 2.

Fig. 3.

Figure 1 is a plan view of an escutcheon, showing my new design.

Figure 2 is a side elevational view.

Figure 3 is a cross-sectional view on the line 3—3 of Figure 1.

The dominant features of the design reside in the portions shown in solid lines.

I claim:

The ornamental design for an escutcheon or similar article, substantially as shown and described.
